US00D895418S

(12) **United States Design Patent** (10) Patent No.: **US D895,418 S**
(45) Date of Patent: ** *Sep. 8, 2020

(54) **BOX**

(71) Applicant: **Jung Sub Kim**, Osan-si (KR)

(72) Inventor: **Jung Sub Kim**, Osan-si (KR)

(73) Assignee: **Jung Sub Kim** (KR)

(*) Notice: This patent is subject to a terminal disclaimer.

(**) Term: **15 Years**

(21) Appl. No.: **35/506,584**

(22) Filed: **Jul. 17, 2018**

(80) **Hague Agreement Data**

Int. Filing Date: **Jul. 17, 2018**

Int. Reg. No.: **DM/200042**

Int. Reg. Date: **Jul. 17, 2018**

Int. Reg. Pub. Date: **Feb. 1, 2019**

(51) **LOC (12) Cl.** **09-03**

(52) **U.S. Cl.**

USPC **D9/419**

(58) **Field of Classification Search**

USPC D9/414-420, 432, 423, 721, 737, 456,
D9/761; D28/78, 83, 77; D27/187, 189;
